United States Patent Office.

KARL MÜLLER, OF NEW YORK, N. Y., ASSIGNOR TO NICHOLAS MÜLLER, OF SAME PLACE.

Design No. 3,645, dated August 31, 1869.

DESIGN FOR A CLOCK-CASE.

The Schedule referred to in these Letters Patent and making part of the same.

To all whom it may concern:

Be it known that I, KARL MÜLLER, of the city, county, and State of New York, have invented a new and useful Design for a Clock-Case; and I do hereby declare that the following is a full and exact description thereof, reference being had to the accompanying photograph, forming a part of this specification, in which the design is represented by a front view.

This invention relates to a design for a clock-case.

For convenience in description, it may be divided into two parts, *a a* the upper part, and *b b* the pedestal or base.

The main feature of the part *a a* is a figure of a miner or gold-digger, *c*, who leans against an old, patched boiler, *d*, which forms the background of the part *a a*.

The miner stands with his legs crossed, his pantaloons in his boots, his shirt-front is thrown open. He leans his head on his left arm, the elbow resting on the boiler. In his right he holds a miner's shovel, which crosses his legs, and rests on the ground. Behind the shovel, leaning against the boiler, are various

picks, &c., and thrown across the top of the boiler lies the miner's coat. In front of it, (the boiler,) under the coat, is the dial-hole *e*, while below that stands a young bear, *f*.

The lower rim of the part *a a* is formed by a series of lozenge-shaped buttons.

The base or pedestal *b b* is embellished by ornaments in relief, the background being filled out with ivy-leaves.

On this part, *b b*, directly under the miner's figure, is a leopard's head, and on each side of the pendulum-sash, *G*, are an eagle's and a prairie-dog's heads, all in relief, as may be seen in the photograph.

What I claim as my invention, and desire to secure by Letters Patent, is—

The design for a clock-case, as herein shown and described.

KARL MÜLLER.
